CLAIM

I claim the ornamental design for drying rack, as shown and described.

DESCRIPTION

FIG. 1 is a left-side/front/top isometric view of a drying rack showing my new design in an open condition;

FIG. 2 is a left-side/ front/top isometric view thereof in a closed to condition;

FIG. 3 is a front elevational view thereof in the closed condition, the rear elevational view being a mirror image and, therefore, not shown;

FIG. 4 is a top plan view thereof in the closed condition;

FIG. 5 is a bottom plan view thereof in the closed condition;

FIG. 6 is a right-side elevational view thereof in the closed condition; and,

FIG. 7 is a left-side elevational view thereof in the closed condition.
